EDGAR N. DOLLIN, OF SYRACUSE, NEW YORK.

WINDOW LIFT.

Application filed October 20, 1920. Serial No. 418,216.

To all whom it may concern:

Be it known that I, EDGAR N. DOLLIN, of Syracuse, in the county of Onondaga, in the State of New York, have invented new and 5 useful Improvements in Window Lifts, of which the following, taken in connection with the accompanying drawings, is a full, clear, and exact description.

This invention relates to a device commonly known as a "window lift" for opening and closing the movable windows of vehicle bodies, although it is evident that it may be used in other relations wherever applicable in converting rotary motion into reciprocal motion.

The main object is to provide simple and efficient means for easily and quickly adjusting the window to either extreme or to any intermediate position, and automatically locking the same in any position of adjustment without the aid of extra locking means.

One of the specific objects is to utilize a relatively "low pitch" and short throw, 25 rotary cam or eccentric preferably of the spiral type in the operation of a relatively "long throw" system of levers in the form of "lazy tongs" to which the window is attached so that a relatively short movement of the levers engaged by the spiral bearing will cause a considerably greater movement of the opposite end levers carrying the window in a plane at substantially right angles 30 to the axis of movement of the cam or eccentric.

Another object is to simplify the method of assembling the window operating parts in and upon the door or panel of the vehicle body so that the entire window, including 40 the operating parts, may be easily and quickly removed for repairs or re-adjustment when necessary.

A further object is to provide means in the form of coil springs connected to the 45 upper ends of the lazy tong levers for partially counterbalancing the weight of the window whereby the latter may be more easily raised and lowered without overstraining any of the operating parts.

Other objects and uses relating to the 50 specific device will be brought out in the following description.

In the drawings—

Figure 1 is an inner face view of a window for motor vehicle bodies and improved

operating means therefor, portions of the window frame of the body being shown at opposite side of the window, which is also shown by dotted lines in its partly elevated position.

Figure 2 is an enlarged horizontal sectional view of the same device taken on line 2—2, Figure 1.

Figure 3 is an enlarged inner face view of the rotary disk and spiral bearings thereon.

Figures 4, 5 and 6 are enlarged sectional views taken respectively in the planes of lines 4—4 and 5—5, Figure 2 and 6—6, Figure 1.

Figures 7 and 8 are perspective views of the detached interlocking plates for receiving the operating shaft of the spiral disk.

Figure 9 is a perspective view of the detached spring lock for holding the disk shown in Figure 8 against turning movement relative to the outer cap section.

Figure 10 is a perspective view of the outer cap section for receiving the same shaft.

Figure 11 is a perspective view of the shaft.

Figure 12 is a perspective view of the detached hand lever.

Figure 13 is a detailed sectional view of a portion of the spirally ribbed disk together with the adjacent portion of the body panel and one of the locking disks shown in Figure 7.

Figure 14 is a top plan, partly in section, of the outer cap together with the shaft therein and the hand lever on the shaft.

The window, —A— to be operated, is movable vertically in a guide opening or pocket —b— in the door or panel —B— of the vehicle body, and has its lower edge seated in a grooved supporting rail —a— having a central pendant extension —a'— for attachment to the operating means hereinafter described.

The inner wall of the opening —b— of the door or panel —B— in which the window is mounted is provided with a circular recess —b'— for receiving the circular body portion of a metal casing or housing —1— which is provided with a marginal flange —2— and cover plate —3—, both secured by screws or bolts —4— to said wall around the recess —b'—, said casing being provided with a reduced central hub seated in a correspondingly reduced

portion of the recess —b'— to form a bearing for one of the rotating parts of the window lifting means.

Portions of the marginal flange at diametrically opposite sides of the case are cut away to form radial openings therethrough and the corresponding sides of the cover plate are provided with laterally projecting pairs of arms —5— which extend through the openings in the flange and are also fastened to the inner wall of the frame —B—, those of each pair being spaced one above the other and having their adjacent edges offset to one side to form parallel guides for certain parts of the window lifting mechanism presently described.

Window lifting mechanism.

A disk —6— of metal is rotatably mounted within the casing —1— and is provided with a central hub —7—, at one side journaled in the bearing —1'—, the opposite or outer side being provided with a spiral groove —8— forming a spiral rib —9—, both of which extend several turns eccentrically around the axis of the disk as shown more clearly in Figure 3 for receiving and engaging a pair of studs or rollers —10— which are mounted upon the adjacent ends of a pair of opposite radially extended links —11—, Figure 2, for imparting reciprocal motion to the links as the disk is rotated in reverse directions.

That is the studs or rolls —10— are engaged in the groove —8— at opposite sides of the axis of the disk and when the window is in its extreme down position are engaged in the portions of the groove nearest said axis whereby when the disk is rotated in the proper direction or to the right, Figure 3, as indicated by arrow X, the studs or rolls —10— and links —11— will be gradually moved away from said axis, while the rotation of the disk in a reverse direction will, of course, return those parts toward the axis.

The links —11— extending horizontally across the open sides of the groove —8— within the housing —1— and thence outwardly through openings —12— in the peripheral walls of said case where they are bent outwardly through the slots between the horizontal guides —5— and then parallel therewith, the portions of the links at the outer side of the casing being provided with rollers —13—, which move in said slots along and upon the guides and serve to hold their respective links in substantially horizontal planes. A system of vertically movable levers —14—, constituting lazy tongs, have their lowermost levers pivoted to each other and to the extension —a'— of the support —a— for the window —A—, while the upper ends of the upper levers are connected respectively to the links —11—

preferably coaxial with the outermost rolls —13— whereby the reciprocatory movement of the links, by the rotation of the disk —6—, will be transmitted to the upper ends of the upper levers of the lazy tongs to open and close the same and thereby to cause the raising and lowering of the window.

The weight of the window is partly counterbalanced by a pair of coil springs —15—, having their outer ends attached to suitable anchored eyes —16— in the frame —1— and their inner ends attached to the adjacent ends of the links —11—, as shown more clearly in Figure 1, thereby permitting the window to be raised with greater ease and less power than would be the case, if the springs were omitted. The inner ends of the levers —11— are also provided with outturned lugs —17— which ride along and upon suitable guides —18— in the coverplate —3— to additionally hold the links against vertical displacement. Suitable roller ball bearings —19— may be interposed between the inner face of the disk —6— adjacent wall of the casing —1— to reduce friction when the disk is rotated, the opposite face being provided with a circular boss —20— bearing against the inner face of the coverplate to hold the disk against outward displacement.

Hand lever attachment.

The hub —7— of the disk —6— is provided with a socket —21— of angular cross section for receiving the inner end of the rotary shaft —22— of similar angular cross section, said shaft being extended inwardly from the inner end of the hub beyond the inner face of the door or panel —B— and is provided at its outer end with a hand lever or crank arm —23— rigid thereon and by which the shaft may be rotated in reverse directions to impart similar motion to the disk.

The shaft —22— is held in position by suitable plates —24— and —25— and a cap —26—, all of which parts are assembled coaxially with and upon the shaft —22— in such manner that the shaft with the lever —23—, cap —26— and plate —25— may be easily and quickly removed or replaced when necessary without disturbing any of the other parts of the window lifting mechanism.

For this purpose the plate —24— is secured by screws —27— to the inner face of the door or panel —B— and is provided with a series of, in this instance, three, inwardly projecting headed studs —28— arranged in uniformly spaced relation circumferentially about the axis of the shaft —22— and adapted to interlock with a corresponding number of key-hole slots —29— in the plate —25—, both of said plates consisting of circular metal disks of substantially the

same diameter and provided with central shaft openings —30— and —31— respectively.

The shaft opening —30— in the disk —24— is circular, and of substantially the same diameter as that of the portion of the shaft —22—, which passes through to form a bearing therefor. The shaft opening —31— in the disk —25— is provided with a relatively larger portion —32—, the portion —32— being of sufficient size to permit the passage of the shaft —22— therethrough, while the portion —33— is of substantially the same radius as that of a reduced portion —22'— of the shaft said reduced portion forming an annular groove in which the walls of the smaller portion —33— of the shaft opening —31— enter when the parts are assembled to hold the shaft against inward endwise movement.

The plates —24— and —25— are seated in a socket —34— in the cap —26—, the plate —25— being secured to the inner wall of said socket by screws —35— when engaged with the groove formed by the reduced portion —22'— of the shaft.

When the plates —24— and —25— are interlocked with each other by the insertion of the studs —28— through the key-hole slots —29—, the heads of said studs projecting slightly beyond the inner face of the plate —25— and are adapted to enter recesses —36— in the adjacent or the inner wall of the socket —34. Each recess —36— is, however, circumferentially elongated for receiving bow springs —37—, which are placed under tension by engagement of the heads of the studs —28— therewith and are provided with sockets —38— into which the heads of the studs are adapted to ride as the disks —24— and —25— are turned relatively to each other in the act of interlocking the studs in the key-hole slots —29—, thereby frictionally holding the cap —26— and plate —25—, secured thereto, against turning movement relatively to the plate —24—, as the shaft —22— is rotated by its hand lever —23—.

On the other hand, if it is desired to remove the shaft —22— with the handle —23—, disk —26— and plate —25— thereon, the cap —26— with the plate —25— therein may be turned by hand in the proper direction for causing the larger ends of the key-hole slots to register with the heads of the studs —28—, whereupon the shaft with the handle —23—, cap —26— and plate —25— may be withdrawn inwardly endwise away from the plate —24— and panel —B—, it being understood that the larger ends of the key-hole slots —29— are slightly larger than the heads of the studs —28—, while the remaining portions of the slots are of slightly less width than the diameter of said heads.

In assembling the parts of the shaft attachment, the plate —24— is permanently secured to the inner face of the door or panel —B— with its central opening —30— coaxial with the disk —6—. The cap —26— and plate —25— are preferably placed over and upon the shaft —22— before the handle —23— is secured to the inner end of said shaft, the disk —25— being placed over the larger portions of the shaft in eccentric relation thereto until it is registered with the reduced portion —22'— whereupon it may be moved to concentric relation to the shaft and then fastened by the screws —35— to the inner wall of the cap —26—, which is seated closely upon the shaft and, therefore, holds the disk —25— against radial movement, assisted by the engagement of the periphery of said disk with the peripheral walls of the socket —34— after the disk —25— and cap —26— have been properly assembled upon the shaft —22—. The hand lever —23— is placed upon and secured to the inner end of said shaft by any suitable means which will firmly lock the two parts together against relative rotation.

Now, with the plate —24— in operating position upon the inner face of door or panel —B— and the parts —22—, —23—, —25— and —26— assembled in the manner described, the opposite end of the shaft inserted through the opening —30— in the disk —24— and engaged with the angular socket —21— in the hub —7— of the disk —6—, whereupon the cap with the disk —25— secured therein, is turned until the larger ends of the slots —29— are registered with the heads of the studs —28—, thus permitting the cap with the shaft therein to be moved toward the disk —6— until the heads of the studs —28— pass entirely through the slots —29— after which the cap is again turned in the proper direction to cause the smaller portions of the slots —29— to embrace the smaller portions of the studs —28—, while the heads of said studs will ride in the recesses —36— and against the springs —37— until engaged in the sockets —38— which hold the cap against accidental turning movement, it being understood that the ends of this spring —37— are engaged with the ends of the recess —36— to hold said springs against circumferential movement.

Operations.

120

When the parts are assembled in the manner described, and are in their normal positions, with the window down, the rotation of the disk —6— in the direction indicated by the arrow X, Figure 3, will cause the links —11— to be shifted radially in opposite directions away from the axis of said disk, thereby causing a similar spreading of the upper ends of the upper levers of the lazy

130

tongs —14—, which, in turn, will cause a much greater elevation of the lowermost levers and window support connected thereto to elevate the window toward the position shown by dotted lines, Figure 1, the engagement of the studs or rollers —10— with the walls of the groove —8— at diametrically opposite sides of the axis, with the disk serving to lock said links and lazy tongs in their adjusted positions to hold the window in any position of adjustment without extra locking means. A reverse rotation of the disk will, of course, cause the return of the window to its lowermost position. The use of the spiral groove and rib as the means for converting rotary into reciprocatory motion requires but little power, is substantially noiseless and serves to hold the parts operated thereby in any position of adjustment. Other forms of eccentrics or cams may be employed with equal efficiency and various other changes may be made in the detailed construction of the various parts of the window lifting mechanism without departing from the spirit of my invention and therefore, I do not wish to limit myself to the precise construction and arrangement shown and described.

30 By locking the plate —25— of the cap —26— to the baseplate —24— in the manner described or by slight turning movement not only avoided the use of external screws but enables the cap to be brought into close contact with the inner face of the panel and causes it to present a smooth and unbroken appearance and, at the same time, permits the hand lever and shaft together with the cap section —26— and its disk —25— to be 35 easily and quickly withdrawn at any time by simply turning the cap by hand in the proper direction for releasing it from the baseplate —24—.

What I claim is:

45 1. In combination with a vertically movable window, a device for raising and lowering said window, including a pair of hori-

zontally alined guides extending in opposite directions from a point substantially midway between the opposite edges of the window, slides movable in said guides and spring pressed in one direction, and means for moving the slides along the guides against the spring action, and means actuated by the movement of the slides in one direction for imparting a lifting movement to the window.

2. In combination with a vertically movable window, a pair of horizontally alined guides extending in opposite directions from a point between the opposite upright edges of the window, slides movable in the guides and spring pressed in one direction, means operable at will for moving the slides along the guides, and a lazy tongs operatively connected to said slides and to the window for raising the window as the slides are moved away from each other and for lowering the window as the slides are moved toward each other.

3. In combination with a vertically movable window, a pair of horizontally alined guides extending in opposite directions from a point substantially midway between the opposite upright edges of the window, slides movable in said guides, springs for moving the slides along the guides away from each other, a disk rotatable about a horizontal axis in substantially the same horizontal plane as that of the guides and provided with a spiral bearing around said axis and engaging the slides, and a lazy tongs operatively connected to said slides and to the window for raising the window as the slides are moved away from each other and for lowering the window as the slides are moved toward each other.

In witness whereof I have hereunto set my hand this 8th day of October 1920.

EDGAR N. DOLLIN.

Witnesses:

H. E. CHASE,
